[57] CLAIM

The ornamental design for a plastic container, as shown and described.

DESCRIPTION

FIG. 1 is a perspective view thereof looking downwardly from the right;

FIG. 2 is front elevation view thereof;

FIG. 3 is a right side elevation view of the plastic container; the left side elevation view is a mirror image thereof;

FIG. 4 is a rear elevation view thereof;

FIG. 5 is a top plan view thereof; and,

FIG. 6 is a bottom plan view thereof.

The broken lines in the drawings are for illustrative purposes only and do not form part of the claimed design.
